UNITED STATES PATENT OFFICE.

NATHAN C. JOHNSON, OF ENGLEWOOD, NEW JERSEY.

COLLAPSIBLE MANDREL PARTICULARLY ADAPTED FOR MAKING, FORMING, AND PLACING CONCRETE PILING.

1,173,806.

Specification of Letters Patent. Patented Feb. 29, 1916.

Application filed June 4, 1915. Serial No. 32,173.

To all whom it may concern:

Be it known that I, NATHAN C. JOHNSON, a citizen of the United States of America, and a resident of Englewood, county of Bergen, and State of New Jersey, have invented a certain new and useful Collapsible Mandrel Particularly Adapted for Making, Forming, and Placing Concrete Piling, of which the following is a specification.

10 This invention relates to improvements in collapsible mandrels; the mandrel herein described being particularly adapted for use in the making, forming, and placing of piles, or piling, of which the body is composed wholly 15 or in part of concrete. The said mandrel is particularly intended for use in the art of forming what are known as "cast-in-place" concrete piles, wherein a rigid mandrel suitably constructed is placed within and cov- 20 ered by a thin shell of suitable material, the whole driven into the ground and the mandrel collapsed and withdrawn, leaving the thin shell in the ground to form a mold for the reception of fluid concrete, which latter, 25 after setting and hardening, forms the pile proper, as in the system of piling disclosed in U. S. Letters Patent to Raymond, Nos. 589,026 and 806,838. The applications of my improved apparatus are, however, not 30 limited to the uses before specified, but may be applied to any purposes wherein it is desired to utilize a rigid mandrel, capable of later withdrawal, as a force-resistant medium, or forming medium, in the placement 35 or forming of molds, or forms, in the earth, for the reception of concrete which on setting and hardening will form a bearing column, or pile, whether or not a covering, or shell shall be used therewith either as a temporary 40 mold, or as one to remain permanently, both as a mold and as an integral and permanent part of the column, or pile, in the ground; also various other uses for my mandrel exist, and I do not limit my invention to any par- 45 ticular use or uses.

The object of the invention is to provide simple and efficient means whereby a mandrel of the general type shown may be collapsed against severe external strains, as are often occasioned by the "back pressure," or inward pressure, of the earth through and into which the mandrel is driven by blows,

as from a drop hammer, such collapse being necessary for the easy removal of the mandrel.

55 A further object of my invention is to provide a simple, rugged and efficient construction whereby the collapsible mandrel may be expanded against pressure from without, should it be desired to do so.

60 A further object of my invention is to provide a simple, rugged construction such that the component parts of the mandrel, shall, when expanded, operate essentially as a unit, without mutual reactions tending to 65 cause breakage and disruption such as obtain in other types of such apparatus, as, for instance, those wherein tapered bearings are used for causing the expansion of the mandrel, or for permitting its collapse.

70 A further object of my invention is to provide means whereby the mandrel when expanded shall be held by the mutual interactions of simple, rigid members in such state, even against the collapsing action of 75 severe forces such as might be exerted by the "back pressure," or inward pressure of the earth, or by the impact of the driving hammer, until such time as it is desired to cause the collapse of the mandrel; and to provide 80 means whereby that collapse may be easily and quickly effected when desired.

85 A further object of my invention is to effect the collapse of the mandrel positively, yet with simple means and without multi- 85 plication of parts.

90 A further object of my invention is to provide, in a collapsible mandrel for the purposes above indicated, such an arrangement of parts that the mechanism necessary 90 shall be of such character as to admit of a lighter construction than is admissible with other types of like apparatus, so that there shall be less necessary mandrel weight with corresponding decrease of inertia of 95 the apparatus, with resultant increase of penetration for a given blow, or, conversely, a lesser blow, as from a smaller and lighter hammer, required for a given penetration, with resultant economy of driving, or of 100 equipment, or of both.

A further object of my invention is to provide such internal construction in an expanding and collapsing mandrel of the

type shown as to admit of plastic concrete being poured through the interior of the mandrel, thus admitting of the mandrel being used either without a shell, as in those 5 systems of concrete piling wherein the fluid pressure of the plastic concrete is relied on to withstand the back pressure of the earth sustained before its withdrawal by the driven tube, or mandrel, or permitting the 10 use of the same fluid pressure with an unreinforced shell, by incasing the mandrel with such an unreinforced shell before driving, fitting the mandrel with a removable point which remains with the shell permanently 15 in the ground after driving, the collapsing of the mandrel enabling its ready withdrawal from the shell, and the plastic concrete, passing through the mandrel into the shell as the mandrel is withdrawn, aiding 20 the shell to withstand the back-pressure of the earth.

The accompanying figures illustrate the general features of my invention and its application as stated above.

25 In said drawings: Figure 1 shows a sectional elevation of a collapsible mandrel embodying my invention, and driving head, the parts of the mandrel being shown in collapsed position, and two elements only of 30 the mandrel being shown, though in general the mandrel will be composed of a much larger number of similar elements. Fig. 2 shows a transverse section of the casing and mandrel on the line X—X of Fig. 1. Fig. 35 shows a fragmentary vertical section of one of the elements of the mandrel, in relaxed condition. Fig. 4 is a view similar to Fig. 3, but showing the parts in a partly expanded position. Fig. 5 is a further similar view showing the parts in the completely 40 expanded position. Fig. 6 shows a fragmentary horizontal section of the mandrel looking upward, the mandrel being shown in the partly expanded position. Fig. 7 shows a detail perspective elevation of one 45 of the swinging wedge levers. Fig. 8 shows a partial longitudinal section and partial elevation of a mandrel constructed in accordance with my invention, a casing 50 surrounding such mandrel being also shown in section; and Fig. 9 is a similar view except that a taper casing and corresponding taper mandrel are shown. Fig. 10 is a transverse 55 section, and Fig. 11 a fragmentary longitudinal section, of an alternative form of mandrel; and Fig. 12 is a transverse section of a still further alternative form of mandrel.

I will particularly describe my invention 60 with reference to its use in the making, forming, and placing of "cast-in-place" concrete piles; but it will be understood that in so doing I do not limit myself to such particular use of the invention.

The mandrel, or core, as it is sometimes called, whatever its sectional-form, may be made of any number of segments from two up; and I do not limit myself to the particular number of segments of which the mandrel, or core, is made; the particular circular section mandrel, or core, herein illustrated and described being made of three segments. Segmental mandrels, or cores, have been used heretofore in the art of concrete piling, but, as made and used heretofore, the expansion of segments, or leaves, of the mandrel, or core, has usually been brought about by means of wedges mounted upon an interior spindle; in which construction the blows of the hammer by which the pile casing is driven, are partly transmitted to the segments, or leaves, of the core, or mandrel, through the medium of the bearing of such wedges against the leaves of the mandrel; and as the taper of these wedges 85 is usually such as to make this transmission of energy least effective, the driving effect of the hammer, as evidenced in penetration of the mandrel, is decidedly imperfect. Further, in mandrels, or cores, of this old 90 type, the "back pressure" or inward pressure, of the ground, when exerted against the segment, or leaves, must, to be in equilibrium, be transmitted transversely of the core, through the wedge bearings; and this 95 pressure, often amounting to many tons at each wedge-bearing, exerts an upward thrust on the central wedge-spindle, with the result that there is not only a constant tendency to collapse, which must be forcibly resisted by appropriate means, but further, this upward tendency of the central 100 interior spindle causes the driving head to separate from the leaves, with the result that not only is driving progress considerably and appreciably delayed, through the internal consumption of energy in these various actions and reactions, but there is also a constant disruption of the component 105 parts of the core under the impact of the hammer blows. To resist this impact, therefore, the several parts of the core must be made extremely massive; and this necessity results not only in a high inertia factor for 110 the core, which inertia has to be overcome each and every time the core is struck and before penetration can result, but it has the further disadvantage of high-value internal 115 reactions, tending to disrupt the several parts of the core; and of high first cost and 120 depreciation and transportation charges. These disadvantages I overcome in my invention.

In carrying out my invention I employ toggle-joint mechanism with special form 125 and functions for the levers, in common with those functions usual to them.

Referring first to Figs. 1 and 2, reference

characters A designate the leaves of the mandrel, B a separable bottom piece, C a driving head, D, D socketed bearing members attached to the leaves A, E a central 5 spindle and F toggle levers. Each of these toggle levers F is of massive construction, as shown particularly in Fig. 7, and has at its outer end massive trunnions F' fitting within suitable bearing-sockets of the bearing 10 members D; while at its inner end each such lever F has a board bearing F'' whereby it is pinned to the center spindle E. On the under side of each such lever F and integral with it, is an extended rib N having its forward edge N' sharpened to a wedge point. From Fig. 2 it will be apparent that these wedge-points N' are adapted to enter the slots between two adjacent leaves A, and thereby to force such leaves outward in addition to the powerful toggle action when 15 the arms of the levers F are forced down by depression of the center spindle E.

It will further be apparent that in this mandrel there is a double action, first by the 20 levers F acting as toggles, and then by the wedge-points N' acting as wedges, tending to force the mandrel leaves A outward, when the levers F are forced down. This will be especially apparent from comparison 25 of Figs. 1, 3, 4 and 5. By comparison of Fig. 1 with Fig. 3 it will be seen that the first effect of downward motion of spindle E is to force the trunnions F' of the levers F back to the outward extremities of the 30 bearing recesses in the bearing members D; further motion downward of the levers F forces those members D outward, and with them, the mandrel leaves A, owing to the toggle action of the levers F; the wedge 35 points N' being, at the same time, introduced between the adjacent edges of adjacent leaves A, as shown in Fig. 6. When the leaves F are in horizontal position, as shown in Fig. 4, the toggle action of those 40 levers has reached its maximum; and as those levers F move downward below the horizontal position, the toggles themselves 45 are collapsed; but the wedges N' are forced still farther forward, or outward, between 50 the adjacent edges of the mandrel leaves A, as shown in Figs. 5 and 6, until they bear, either against such edges of leaves A, or against the corresponding edges of the bearing members D, or both, thereby exerting a 55 very powerful wedging action tending to hold the mandrel leaves outward; the toggles themselves being at such time partially collapsed and with no pressure on them. It will be evident that any number of mandrel 60 leaves, or segments, with such wedges N' thus thrust between them, will be in stable equilibrium so far as inward thrust is concerned, and that the tendency to collapse due to external pressure will be resisted by

a solid block of material N' in pure compression, and with no pressure on pins, or pivots, or bearings—a most advantageous condition; and it will also be evident that the insurance of a thorough and effective penetration of this block of material, N', is 65 brought about by the relative lever arms of the toggle arms, actuated by the depression of the spindle E, as compared to that of the resisting wedges N' pressed against by the leaves A. It is evident that this is a very 70 75 powerful lever system rendering certain and positive a proper expansion of the leaves.

It is contemplated that the wedges shall be of such dimensions that when those wedges are in the extreme outward position 80 the pressure of the mandrel leaves will be against the parallel faces of those wedges, so that the pressure of the leaves on the wedges exerts no tendency whatever to thrust such wedges inward again. However, the angle of the wedges is so small 85 that pressure of the leaves on those wedges, if exerted upon the oblique faces of the wedges, would be exerted at an angle much smaller than the critical angle of the friction and so would exert no tendency to press the wedges inward. Moreover, it will be noted that if for any reason the wedges should be forced inward, the toggle mechanism must necessarily rise, which would 90 force the trunnions into contact with the bearing pieces D, necessitating an outward thrust on the leaves; and rise of the toggle levers to dead center would be strongly resisted not only by the weight of the center 95 piece E and the latches G connecting the driving head with the leaves, but also by the inward pressure of the earth. This constitutes a double insurance against unintended collapse. 100

When it is desired to effect collapse of the mandrel the central spindle E is raised, and it will be obvious that like actions take place in reverse direction with equal power and efficiency. 105

The driving head, C, is suitably connected to the central spindle E, and is also provided, in practice, with a wooden driving block C' which receives the blows of a hammer. This head C is also provided with slings C'' 110 115 whereby the spindle E may be raised when it is desired to collapse the mandrel.

In practice, the mandrel is usually used (though not necessarily) with a casing I (Fig. 8) or I' (Fig. 9); casing I being 120 straight while casing I' is tapered; the mandrel being modified in construction as shown in Fig. 9 when it is to be used with a tapered casing.

In fitting the mandrel for the reception of 125 the casing, the collapsed mandrel is lifted into the pile driver guides or leads, usually by suitable cables attached to the hammer

by which the mandrel and casing are to be driven, and the point of the mandrel is then dropped upon a suitable support, such as a timber, from a short height. The inertia of 5 the driving head C and the spindle E then serve to cause relative motion between the spindle E and the leaves A so that the mandrel is fully expanded. The driving head C is provided with dogs G which then engage notches A' in the mandrel leaves A. 10 The expanded mandrel as a unit may then be lifted again into the leads so that the casing or shell I (Fig. 8) or I' (Fig. 9) may be slid over the mandrel in sections and 15 drawn into position by suitable means. In the construction herein shown, however, it is possible to effect the advantageous alternative of placing the sections of the casing or shell easily outside of the mandrel before 20 expansion and expanding the mandrel by the procedure outlined above; the mandrel in this latter case being powerfully expanded against the casing or shell I with the result that the casing is tightly bound 25 to the mandrel by friction. The proper engagement of the dogs G with the recess A' may be insured by proper alining means such as the dowels K entering recesses C''' in the driving head C. These dowels, however, 30 are not the only means which may be used for this purpose, and are shown as constituting one of the various suitable devices for holding the leaves in proper registry with the driving head. The casing, with 35 mandrel placed within it, may then be driven into the earth by the action of a hammer in the ordinary way; and it will be noted that the impact of the hammer will be transmitted through the driving head C, direct to the mandrel leaves A and casing I or I', without passing through the toggle mechanism. When the casing has been driven, the mandrel may be collapsed and withdrawn by first releasing the dogs G 40 from the mandrel leaves A and then lifting the driving head by means of the slings C', whereupon the spindle E is lifted, toggle levers F are raised and thereby the wedges N' are withdrawn from between the leaves 45 of the mandrel, and the trunnions F of the toggle levers moved to the position shown in Fig. 1, so entirely collapsing the mandrel and permitting its withdrawal. The bearing members D are provided with hook lugs 50 D' and with corresponding bottom lugs D'' whereby the trunnions F' are, in practice, confined, yet in such manner that the levers F are readily removable from engagement with the bearing pieces D when the leaves 55 A are by proper means moved out at right angles from the center line of the spindle E. In other words, when the mandrel is in relaxed position, the leaves A of the mandrel may be separated from the toggle mech- 60

anism by moving them outward radially, 65 the trunnions F' of the levers F passing through the gaps between the lugs D' and D'' of those leaves. Similarly, it is easy to reengage the mandrel leaves with the toggle mechanism. But while it is easy to 70 engage and disengage the levers of the mandrel with the toggle mechanism, nevertheless the mandrel may be handled without fear of such disengagement occurring, because any upward pull on the driving 75 head C when the toggle mechanism is relaxed, and the mandrel collapsed, draws the trunnions F' into the recesses in the under sides of the lugs D', the leaves of the mandrel then hanging securely from those trunnions. 80

It is obviously immaterial whether the wedges N'—N of the toggles bear against the sides of the leaves themselves, or against the sides of the bearing members D, since 85 these bearing members D are to be considered as being, functionally, parts of the leaves themselves.

Since the mandrel leaves form a nearly complete cylinder, or cone, as the case may be, it is perfectly practicable to drive the mandrel into the ground, without first surrounding that mandrel with a casing; and then, when the mandrel has been driven to a suitable depth, it may be withdrawn 90 and the hole in the earth filled with concrete; or, the concrete required to form the pile may be run in before the mandrel has been removed; (for the mandrel is largely open, inside, affording ample space for the 95 flow of concrete) and then, before the concrete has set, the mandrel may be removed; in which case the concrete will remain in the hole; the point B may, or may not, remain in the hole as desired, and according 100 to the construction of shell, or mandrel, or both, which is employed. And of course, when a casing is used, this casing may be filled with concrete while the mandrel is in place, and then the mandrel removed before 110 the concrete has set.

It is not necessary that the toggle levers F be pivoted across the gaps between the leaves. In Fig. 10 I show a construction wherein the toggle levers, there designated 115 by numerals F^a, are pivoted at the centers of the leaves A^a, and wherein the wedges N^a, N'^a are structurally separated from the toggle levers F^a, but are operated by the same spindle E^a. It is obvious that the 120 operation of this combined toggle and wedge mechanism shown in Figs. 10 and 11 is the same as that of the mechanism shown in the previous figures.

In the further alternative construction 125 shown in Fig. 12, the wedges, N^b, N'^b, are integral with the toggle levers F^b, but are extended laterally from the said levers F^b,

since the latter are pivoted, at the centers of the mandrel leaves A^b; the edges of the mandrel leaves A^b being preferably non-radial, as indicated in Fig. 12.

5. What I claim is:—

1. An expansible and collapsible mandrel comprising a plurality of outwardly and inwardly movable leaves, toggle mechanism for moving said leaves out and in, means 10 for actuating such toggle mechanism and means actuated by said actuating means for relieving the toggle mechanism of pressure and for holding the leaves outward.

2. An expansible and collapsible mandrel comprising a plurality of outwardly and inwardly movable leaves, toggle mechanism for moving said leaves out and in, wedge means for relieving the toggle mechanism of pressure and for holding the leaves outward. 15

20 ward and means for actuating said toggle mechanism and wedge means.

3. An expansible and collapsible mandrel comprising a plurality of outwardly and inwardly movable leaves, toggle mechanism 25 for moving said leaves out and in, means for actuating such toggle mechanism, and wedge means actuated by said toggle mechanism for relieving the toggle mechanism of pressure and for holding the leaves outward.

30 4. An expansible and collapsible mandrel comprising a plurality of outwardly and inwardly movable leaves, toggle mechanism for moving said leaves out and in, means for actuating such toggle mechanism and wedge means actuated by said actuating means for relieving the toggle mechanism of pressure and for holding the leaves outward, said wedge means comprising wedges adapted for insertion between adjacent leaf-edges. 35

5. An expansible and collapsible mandrel comprising a plurality of outwardly and inwardly movable leaves, toggle mechanism for moving said leaves out and in, means for 45 actuating such toggle mechanism, and wedge means actuated by said toggle mechanism for relieving the toggle mechanism of pressure and for holding the leaves outward, said wedge means comprising wedges adapt-

50 ed for insertion between adjacent leaf-edges.

6. An expansible and collapsible mandrel comprising a plurality of outwardly and inwardly movable leaves, toggle levers for moving said leaves out and in, said levers 55 provided with wedges arranged to be thrust between adjacent leaf-edges during the outwardly forcing action of the toggle levers and means for actuating said toggle levers.

7. An expansible and collapsible mandrel 60 comprising a plurality of outwardly and inwardly movable leaves, toggle levers for moving said leaves out and in, said levers provided with wedges arranged to be thrust between adjacent leaf-edges during the out-

wardly forcing action of the toggle levers, 65 and to remain between said leaves after said toggle levers pass the dead center, and means for actuating said toggle levers.

8. An expansible and collapsible mandrel comprising a plurality of outwardly and inwardly movable leaves, toggle levers for moving said leaves out and in, said levers provided with wedges arranged to be thrust between adjacent leaf-edges during the outwardly forcing action of the toggle levers, 70 and to be thrust still farther forward between said edges by motion of the toggle levers beyond the dead center, and means for actuating said toggle levers.

9. An expansible and collapsible mandrel 80 comprising a plurality of outwardly and inwardly movable leaves, toggle levers for moving said leaves in and out, provided with approximately right-angle extensions provided on their outer edges with wedge 85 portions arranged to be inserted between adjacent leaf-edges by expanding motion of said toggle levers, and means for actuating said toggle levers.

10. An expansible and collapsible mandrel comprising a plurality of outwardly and inwardly movable leaves, toggle levers for moving said leaves in and out, provided with approximately right-angle extensions 90 provided on their outer edges with wedge 95 portions arranged to be inserted between adjacent leaf-edges by expanding motion of said toggle levers, said wedge portions arranged to be driven outward still farther between such edges by motion of the toggle levers past and beyond dead center, and means for actuating said toggle levers.

11. An expansible and collapsible mandrel comprising a plurality of outwardly and inwardly movable leaves, means for moving said leaves in and out, comprising means for holding said leaves in the expanded position, and which, when the mandrel is expanded, is free from inward thrust due to pressure on, or shock applied to, said leaves, and comprising also operating means which is relaxed and free from pressure when the mandrel is completely expanded. 105

12. An expansible and collapsible mandrel comprising a plurality of outwardly and inwardly movable leaves, mechanism for moving said leaves in and out, comprising means for holding said leaves in the expanded position, and which, when the mandrel is expanded, is free from inward thrust due to 110 pressure on, or shock applied to, said leaves, and comprising also toggle operating mechanism which is relaxed when the mandrel is completely expanded.

13. An expansible and collapsible mandrel comprising a plurality of outwardly and inwardly movable leaves, each provided with lugs on its inner face having a bearing 125

recess between them, levers for said leaves having trunnions mounted in such bearing recess, the said lugs of said leaves having gaps for the lateral disengagement of the leaves from said lever trunnions, and means connected to said levers for actuating the same.

In testimony whereof I have signed this specification in the presence of two subscribing witnesses.

NATHAN C. JOHNSON.
